UNITED STATES PATENT OFFICE.

JAMES D. STORIE, OF OSHAWA, CANADA.

DRIVING-BELT.

SPECIFICATION forming part of Letters Patent No. 508,153, dated November 7, 1893.

Application filed August 25, 1893. Serial No. 484,014. (No model.)

To all whom it may concern:

Be it known that I, JAMES DOUGLAS STORIE, of the town of Oshawa, in the county of Ontario, and Province of Ontario, Dominion of Canada, have invented a certain new and useful Improvement in Driving-Belts; and I do hereby declare that the following is a full, clear, and exact description of the same, reference being had to the accompanying drawings, forming part of this specification.

My invention relates to belts designed for use on smooth faced wheels, or ordinary pulleys; and it has for its main object to increase the efficiency and durability of such belts. To this main end and object my invention consists in the combination with the usual flat belt of leather, or other analogous belting material, of a metallic chain, or link-belt, which is made somewhat longer than the said flat belt of leather, or other analogous belting material, and which is arranged exteriorly of the said belt, but is left free to travel independently thereof; all as will be found hereinafter more fully described, and as will be more particularly pointed out in the claim of this specification.

Heretofore, a leather belt has been combined with a drive-chain, the chain having been arranged exteriorly of the said belt; but in such case, the chain and leather belts were of equal lengths and were fastened together, so that they had to travel, or run, in company at every point through their length; and the result has been that in the use of such a device the softer and distensible leather band would stretch and become buckled, or crimped, and the action of the combined parts has been found to be inefficient and unsatisfactory. I have found that, by combining with a leather, or other analogous belt, a somewhat longer link-belt, or metallic chain, arranged exteriorly of the leather belt; and leaving the two bands free to travel independently of each other, so that the outer metallic belt can travel faster than the inner leather band, the draft-strain will be divided between the two bands; the metallic belt, however, taking all excessive strain that would tend, or operate, to injuriously affect the inner leather band, while the latter, without being subjected to extensive tensile strain, will afford all the adhesive quality necessary to insure the action

of the duplex drive-belt under excessive draft-strain, without any slip on the pulley faces. And I propose to provide for use a drive-belt, 55 constructed upon this novel principle of action, which will be more efficient and cheaper than any heretofore known, or used, to my knowledge.

To enable those skilled in the art to which my improvement relates, to make and use driving-belts, embodying my invention, either in the precise form herein shown, and described, or in some other I will now proceed to more fully describe my novel construction 55 of endless band, for the transmission of power and motion, referring by letters to the accompanying drawings which form part of this specification, and in which I have shown my said invention carried out in precisely that 70 form of driving-belt in which I have, so far, successfully practiced it.

In the drawings, Figure 1 is a side view of a pair of smooth faced wheels, or ordinary pulleys, banded together, with one of my improved, combined leather-band and endless-chain, driving-belts. Fig. 2, is a partial view, on an enlarged scale, of the compound, leather and metallic driving-belt seen at Fig. 1. Fig. 3 is a side view of the drive pulley seen at the 80 left hand side of Fig. 1, and a portion only of the driving belt, but showing the pulley of larger size.

In the several figures the same parts will be found always designated by the same letter 85 of reference.

E and E' are two ordinary smooth faced pulleys (mounted on suitable shafts) that one marked E being represented as the driver and the one marked E' as the driven; while A is 90 an endless band, or belt, of leather, arranged in connection with the pulleys in about the usual manner, and B is a metallic chain, or endless, link-belt, that is somewhat longer than the belt A, and encompasses the leather-band A, and, as shown, is arranged centrally thereof, in the direction of the width of the latter; all as clearly shown in the drawings.

The faces of the pulleys E and E' are, of course (as usual), of slightly greater circumference at the middle portion than at the edges of the wheels' peripheries (for the well-known purpose of preventing the leather drive-belt A from "running off" either of the

wheels) and, therefore, it is necessary to provide some means of preventing the narrower link-belt, or chain B, from running off the leather band; which latter, of course, assumes 5 (wholly, or partially) the convex form, in cross section, peculiar to the pulley-faces.

In the case shown, the series of leather cross-bars C, which are riveted near their ends (as shown at D) to the belt A, and which 10 loosely confine the chain B laterally, serve to hold the chain in place, and compel it to travel in a path about coincident with the middle (widthwise) of the band A; but some other device or expedient may, of course, be used 15 to serve the purposes of these retaining devices.

It will be seen that the endless chain B is materially longer than the leather belt A, which, as usual, is banded taut on the pulleys; and it will be understood that said chain 20 B is perfectly free to move (longitudinally) independently of the belt A, throughout its entire length; and in these structural features of the combined leather and chain belts 25 shown, lies the important and indispensable characteristic of my invention.

It is by reason of having the link-belt, or chain longer than the leather band and the two endless bands free to travel, at slightly 30 different speeds (the chain B creeping along on the exterior surface of the leather belt A, or gaining on it, slightly, all the time, so to speak), while both bands move in the same direction, that the link-belt is rendered capable 35 of taking the draft strain, while, at the same time, all stretch, or elongation, of the leather belt, from one, or another, cause, is allowed to form slack at the vicinity of that run 40 of the combined belts where the chain is slack, and thus avoid all crimping, buckling and puckering of the leather belt, where the chain exerts a draft strain on it.

Although the chain B is made materially longer than the leather band A, the discrepancy 45 between the two will be reduced some during continued use, by the stretching of the band A; but never to such an extent that the chain will not be longer than the leather band;

for to the difference in length between the two belts is due the above described action 50 that is peculiar to my improved compound driving belt.

In the operation of a driving belt made according to my invention, the narrower and cheaper, but inextensible and more durable 55 chain B, sustains the greater part of, or all the excessive draft-strain, to which the said driving-belt is subjected; while the wider and more expensive; but easily stretched and less durable leather band A, performs wholly the 60 function of the adhesive device of the compound drive-belt; without, however, being stretched and soon worn out, or rendered unserviceable. Hence, where the surrounding 65 circumstances render it necessary, or, for the sake of economy, it is expedient to use a comparatively narrow leather belt, such narrow belt, in combination with the exteriorly arranged chain can be made to do more work—i. e., transmit more power—while at the same 70 time it will last much longer, (at less cost for the original outlay) than a leather belt of greater width.

Of course, the proportionate sizes and degrees of strength of the leather and link-belts 75 shown; their relative lengths; and other details, may, and under varying circumstances will need to be, changed, more or less, within the judgment of the experienced mechanic, or engineer, using my invention.

What I claim as new, and desire to secure by Letters Patent, is—

A driving-belt comprising an inner band of leather, or other material adapted to run in frictional contact with pulley faces; and a 85 link-belt, or drive-chain, arranged exteriorly of said band and free to move, relatively to said band, in a longitudinal direction; all substantially in the manner and for the purposes set forth.

In witness whereof I have hereunto set my hand this 14th day of July, 1893.

JAS. D. STORIE.

In presence of—

W. E. DYER,
JOHN DYER.
